CLAIM

The ornamental design for a staple cartridge assembly for linear surgical stapler, as shown and described.

DESCRIPTION

FIG. 1 is a perspective view of a staple cartridge assembly for linear surgical stapler, showing our new design;

FIG. 2 is a front elevational view of the staple cartridge assembly for linear surgical stapler of FIG. 1;

FIG. 3 is a rear elevational view of the staple cartridge assembly for linear surgical stapler of FIG. 1;

FIG. 4 is a first side elevational view of the staple cartridge assembly for linear surgical stapler of FIG. 1;

FIG. 5 is a second side elevational view of the staple cartridge assembly for linear surgical stapler of FIG. 1;

FIG. 6 is a top plan view of the staple cartridge assembly for linear surgical stapler of FIG. 1; and,

FIG. 7 is a bottom plan view of the staple cartridge assembly for linear surgical stapler of FIG. 1.

The broken lines shown in the drawings are included for the purpose of illustrating portions of the staple cartridge assembly for linear surgical stapler and form no part of the claimed design.
